(57) **CLAIM**

I claim the ornamental design for the insect trap, as shown and described.

DESCRIPTION

FIG. 1 is a top view of an insect trap;

FIG. 2 is a front view of the insect trap of FIG. 1;

FIG. 3 is a bottom view of the insect trap of FIG. 1;

FIG. 4 is a rear view of the insect trap of FIG. 1;

FIG. 5 is a cross-sectional side view of the insect trap of FIG.

1 with the arrows of FIG. 4 showing the direction of view;

FIG. 6 is a side view of the insect trap of FIG. 1; and,

FIG. 7 is a side view of the insect trap of FIG. 1 that opposes the side view of FIG. 6.

The broken line showing of portions of the insect trap are included for the purpose of illustrating only and form no part of the claimed design.
